UNITED STATES PATENT OFFICE.

JOHN POLHAMUS, OF NEW YORK, N. Y.

DESIGN FOR SPOON AND FORK HANDLES.

Specification forming part of Design No. **7,585**, dated July 21, 1874; application filed June 23, 1874.
[Term of Patent 7 years.]

To all whom it may concern:

Be it known that I, JOHN POLHAMUS, of the city and State of New York, have invented or produced a Design for the Handles of Spoons, Forks, &c., of which the following is a description:

The general configuration of the handle at the end may be elliptical, and made with coves at *a*, near the tapering portion of the stem of the handle, and at the extreme end of the handle is a scroll-ornament, *c*. The surface is ornamented with a bead or thread around the edges of the handle, and a central rib, *e*, runs along the stem of the handle with a leaflet, *f*, from which the ribs diverge in the form of a

loop and inclose a foliated ornament, *h*. Between the loop-shaped rib and the edge the surface is ornamented with a running vine in relief. At the end of the rib *e*, next the spoon or fork, there is a foliated ornament, *r*.

I claim as my invention—

The design of the ornamentation upon the surface of the handle, substantially as described and represented.

Signed by me this 19th day of June, 1874.

JOHN POLHAMUS.
